(57) **CLAIM**

The ornamental design for a surgical saw blade, as shown and described.

DESCRIPTION

FIG. 1 is a top view of the surgical saw blade;
FIG. 2 is a side view of the surgical saw blade shown in FIG. 1;

FIG. 3 is an end view of the surgical saw blade shown in FIG. 1; and,

FIG. 4 is a perspective top view of the surgical saw blade shown in FIG. 1.

The broken line showing of the cutting portion of the blade is for illustrative purposes only and forms no part of the claimed design.
